UNITED STATES PATENT OFFICE.

THOMAS B. HUNT, OF CHICAGO, ILLINOIS.

COMBINED FRICTION AND DIRECT-ACTING SPRING DRAFT-RIGGING FOR RAILWAY-CARS.

SPECIFICATION forming part of Letters Patent No. 748,951, dated January 5, 1904.

Application filed June 24, 1903. Serial No. 162,899. (No model.)

To all whom it may concern:

Be it known that I, THOMAS B. HUNT, a citizen of the United States, residing in Chicago, in the county of Cook and State of Illinois, have invented a new and useful Improvement, 5 in a Combined Friction and Direct-Acting Spring Draft-Rigging for Railway-Cars, of which the following is a specification.

My invention relates to combined friction and direct-acting spring draft-rigging for railway-cars.

The object of my invention is to provide a combined friction and direct-acting spring draft-rigging of a simple, strong, efficient, 15 and durable construction, the side plates or stop-castings of which may be of simple ordinary form and applied to the draft-timbers or center sills of the car in the ordinary manner.

20 My invention consists in the means I employ to practically accomplish this object or result—that is to say, it consists, in connection with the car-coupler, draw-bar, draw-bar extension, and a pair of side plates or stop-cast- 25 ings having front and rear stops, of a transversely-acting spring, a longitudinally-acting spring, followers, a pair of transversely-movable friction plates or blocks having oppositely-inclined friction-faces, and a longitudi- 30 nally-movable friction shell or barrel having a pair of oppositely-inclined friction-faces en- 35 gaging the corresponding friction-faces on said friction plates or blocks, the rear follower under pulling strains moving said friction shell or barrel with the draw-bar, while the front follower holds the transversely-movable plates or blocks from longitudinal movement and through them holds the middle follower also stationary, and thus compresses both the 40 longitudinally-acting and the transverse-acting springs, and under buffing strains the rear follower holding said friction shell or barrel stationary, while the front follower moves the transversely-movable friction plates or blocks 45 longitudinally with the draw-bar and through them the middle follower also, thus causing both the longitudinally-acting and the transversely-acting springs to be compressed and adding in both cases or under both pulling and 50 buffing strains the frictional resistance of the inclined friction-faces on the shell and friction-plates to the resistance of the springs.

My invention also consists in the novel construction of parts and devices and in the novel combinations of parts and devices here- 55 in shown or described.

In the accompanying drawings, forming a part of this specification, Figure 1 is a central vertical longitudinal section of a draft-rigging embodying my invention, taken on the line 1 1 of Fig. 2. Fig. 2 is a horizontal section on line 2 2 of Fig. 1. Fig. 3 is a cross-section on line 3 3 of Fig. 2. Fig. 4 is a detail perspective view of the rear follower. Fig. 5 is a detail perspective view of one of the 65 transversely-movable friction plates or blocks, and Fig. 6 is a detail perspective view of the friction shell or barrel.

In said drawings, A represents the draft-timbers, A' the center sills, A² the cross-sill, 70 A³ the buffer-block, A⁴ the buffer-plate, and A⁵ the carry-iron, of a railway-car.

B is the draw-bar of the coupler. B' and B² represent the draw-bar extension, the same being preferably in the form of a yoke, 75 secured to the draw-bar by the rivets b and interengaging shoulders b' b².

C, C', and C² are the followers, and D D are the side plates or stop-castings, the same having front and rear stops d and d' for the followers 80 to abut against and upper and lower guides d² d³ in or on which the followers reciprocate, the lower guides d³ being removably secured in place by bolts d⁴ to facilitate the insertion and removal of the draft-rigging. 85

E is a longitudinally-arranged spring between the middle and rear followers C' C², and F is a transversely-arranged spring between the transversely-movable friction plates or blocks G G. The transversely-movable friction plates or blocks G G have oppositely-inclined friction-faces g g, which bear against the corresponding inclined friction-faces h h on the longitudinally-movable friction shell or barrel H, which is preferably 90 rectangular in cross-section, as shown in the drawings. The longitudinally-movable friction shell or barrel H has interior shoulders h² h³ for the middle follower C' to abut against. The transversely-movable friction plates or blocks G G are interposed between the front and middle followers C C', and the friction of their end faces g² g³ against the followers affords a material resistance in ad- 95

- dition to the resistance produced by the friction of the inclined friction-faces $g\ g$ of said plates against the similarly-inclined friction-faces $h\ h$ of the shell or barrel H. The friction plates or blocks G G are chambered out at $g^5\ g^5$ to give additional length or room for the transversely-acting spring F.
- As the transversely-movable friction-plates G G under tension or thrust of the transversely-acting spring F bear directly against the surrounding or confining friction shell or barrel H, it will be understood that in my invention the side plates or stop-castings D D and the draft timbers or sills to which they are secured are entirely relieved from lateral thrust of the transversely-acting spring, and thus from any transverse blows or shocks, which would otherwise be transmitted to them from the draw-bar through the transversely-acting spring. I thus in my invention secure all the advantages of a transversely-acting spring and a frictional resistance actuated thereby without any of the disadvantages or weaknesses ordinarily incident thereto.
- 25 The rear follower C² is preferably provided with integral flanges or casings C³ C³ to enclose the longitudinally-acting spring E at the sides and to serve as stops to limit the compression of the longitudinally-acting spring.

Inside the springs E and F smaller springs E' and F' are preferably employed, as is customary.

The side plates or stop-castings D D are secured to the framework of the car in the usual manner by bolts d⁵ d⁵.

In operation under buffing strains the rear follower C² and the friction shell or barrel H are held stationary by abutment against the rear stops d' of the side plates or stop-castings, while the front and middle followers C C' and the transversely-movable friction plates or blocks G G move rearwardly with the draw-bar, thus compressing the longitudinal or direct-acting spring E and also the transversely-acting spring F and causing the transversely-movable friction plates or blocks G to move toward each other against the frictional resistance encountered by the inclined friction-faces g g and h h and that of their straight friction-faces g² g² against the followers C C'. Under pulling strains the operation is the same, excepting that in this case it is the front follower C and the friction-plates G G which are held from longitudinal movement by abutment against the front stops d d of the side plates or stop-castings, while the rear follower C² and the friction shell or barrel H move with the draw-bar.

I claim—

1. In a combined friction and direct-acting spring draft-rigging, the combination with a draw-bar, draw-bar extension, side plates or

stop-castings and followers, of a longitudinally-acting spring, a transversely-acting spring, a pair of transversely-movable friction plates or blocks, and a longitudinally-movable friction shell or barrel, substantially as specified.

2. In a combined friction and direct-acting spring draft-rigging, the combination with a draw-bar, draw-bar extension, side plates or stop-castings and followers, of a longitudinally-acting spring, a transversely-acting spring, a pair of transversely-movable friction plates or blocks having inclined friction-faces, and a longitudinally-movable friction shell or barrel having inclined friction-faces engaging the inclined friction-faces of said transversely-movable friction plates or blocks, substantially as specified.

3. In a combined friction and direct-acting spring draft-rigging, the combination with a draw-bar, draw-bar extension, side plates or stop-castings and followers, of a longitudinally-acting spring, a transversely-acting spring, a pair of transversely-movable friction plates or blocks having inclined friction-faces, and a longitudinally-movable friction shell or barrel having inclined friction-faces engaging the inclined friction-faces of said transversely-movable friction plates or blocks, said longitudinally-movable friction shell or barrel having shoulders for the middle follower to bear against, substantially as specified.

4. In a combined friction and direct-acting spring draft-rigging, the combination with a draw-bar, draw-bar extension, side plates or stop-castings and followers, of a longitudinally-acting spring, a transversely-acting spring, a pair of transversely-movable friction plates or blocks having inclined friction-faces, and a longitudinally-movable friction shell or barrel having inclined friction-faces engaging the inclined friction-faces of said transversely-movable friction plates or blocks, the rear follower having an integral flange or case to limit the compression of said longitudinally-acting spring, substantially as specified.

5. The combination with a draw-bar, draw-bar extension, side plates or stop-castings and followers, of a transversely-acting spring, a pair of transversely-movable friction-blocks against which said spring bears and having inclined friction-faces, and a longitudinally-movable friction shell or barrel surrounding and taking the lateral thrust of said transversely-movable friction-blocks and having inclined friction-faces engaging the inclined friction-faces of said longitudinally-movable friction-blocks, substantially as specified.
